UNITED STATES PATENT OFFICE.

ALBERT ENNIS HENDERSON, OF TORONTO, ONTARIO, CANADA.

TUBE FOR PNEUMATIC TIRES.

Application filed January 22, 1917. Serial No. 143,911.

To all whom it may concern:

Be it known that I, ALBERT ENNIS HENDERSON, a subject of the King of Great Britain, residing in Toronto, Province of Ontario, in the Dominion of Canada, have invented new and useful Improvements in Tubes for Pneumatic Tires, of which the following is a specification.

My invention relates to improvements in inner tubes in which the tube is provided with means to prevent the pinching of the tube by the bead of the casing in that portion of the tube adjacent to the rim of the wheel. In my co-pending application I have shown protecting fabric arranged in strips longitudinally around the rim side of the tube overlapping longitudinally and transversely.

The objects of my present improvements are:

First. To provide a tube which carries on or imbedded in its rim side the means whereby it is protected from pinch or injury.

Second. To arrange the protection in such manner as to permit longitudinal, transverse and diagonal expansion of the protected side of the tube.

Third. To arrange the protecting strips in such manner as to provide a number of openings which would be suitable for being apertured to receive the valve stem.

Fourth. To uniformly imbed the said protecting means in the rim side of the tube.

Fifth. To provide a suitable rim side protection which will be adapted to co-operate with any protected and thickened tread designed to overcome the effect of punctures in the tread side of the tube.

I attain these objects by the mechanism illustrated in the accompanying drawings.

Fig. 1 is a plan view showing a section of the tube with my improved device applied.

Fig. 2 is a transverse section of the tube as shown in Fig. 1, through the line AB.

Fig. 3 is a plan view of a portion of the tube showing the addition of an extra piece of valve base fabric.

Fig. 4 is a modified plan view showing the relation of the protecting fabric at the ends of the tube.

Fig. 5 is a plan view showing the relation of the fabric in the rim side of the tube to that in the tread portion.

Fig. 6 is a cross section of Fig. 5 showing the transverse relation of the parts.

Similar reference characters refer to similar parts throughout the several views.

In Fig. 1 I have shown a section of the tube 7 showing in elevation in its central portion 8 the relation of the strips 9 and 9' in dotted line formation with the valve stem 10 having the button 11 and the reduced portion 12 in position to be inserted from without in the hole 14. I also show in similar relation to the diagonal strips the hole 14', which might also be punched for the reception of the valve stem. I have shown a portion of the rubber of the tube broken away at 15 showing in plan view the strips 9 separated by the rubber of the tube 16 and the relation of the strips 9' shown in dotted lines. On the reverse end 75 of the tube I have shown the rubber of the tube cut away at 17 showing a portion of the fabric strips 9, and again cut away at 18, showing the position of the fabric strips 9' with the separating strips of rubber 19. 80

In Fig. 2 are shown the strips 9 and 9' in their transverse relation to each other in the line AB of Fig. 1.

In Fig. 3 is shown a section of the tube 7' in which the rubber is cut away at 20, showing the additional fabric base piece 21 having the slot 22, superimposed upon the diagonally arranged strips 9 and 9', the central point of the slot 22 being superimposed above the point of intersection of the spaces between the strips 9 and 9', as shown in Fig. 1, at the point 14'. The rubber of the tube is further broken away at 23, showing the strips 24, which correspond to the strips 9 in Fig. 1 in their relation in the tube; the said strips 24 and the rubber are further broken away at 25, showing the film of rubber 26 separating the strips 24 from the strips 24', which are shown in elevation together with the separating rubber 27, 100 which separates the individual sections of the series 24' from each other diagonally. The strips 24' and the rubber 28 of the tube are further broken away at the right showing the relation of the strips 24' to the inferior surface of the tube.

In Fig. 4 I show sections of the tube 7" having parts broken away at 29, 30 and 31, showing the relation of the fabric strips in the body of the tube, while at the end 32 I show the fabric strips 9 and 9' projecting and adapted to overlap with the strips 9

and 9' which are shown exposed at 33 and 34, when the ends of the tube are joined together. The tube is broken at 35.

In Fig. 5 I have shown a section of the tube 7" showing in elevation the rim side fabric strips 9 and 9' in relation to each other. I have broken away a portion of the tube at 36 showing in plan view the tread portion of the tube in which the thickened rubber portion 37 is broken away showing the fabric strips 38 and 38' separated longitudinally by the rubber 39 and broken transversely at 40 and 40'. The strips 38 and 38' and the rubber of the tube are broken away at 41, showing the strips 42, 42' and 42'', imbedded in the rubber of the tube and separated by the film of rubber 41' from the strips 38 and 38', the said strips 42, 42' and 42'' being separated from each other longitudinally by the strips of rubber 43 and 43', and also broken transversely at 44, 44' and 44''; thus it will be seen that the tube is not only provided with the rim side protecting strips, but also with the tread compressing strips in overlapping formation.

In Fig. 6 I have shown a cross section of Fig. 5 on the line CD, showing the transverse relation of the parts in both the tread and rim sides of the tube.

I have thus illustrated and described a new and improved form of tube having protection applied on the rim side of the tube designed to yield longitudinally, transversely and diagonally, and providing an elastic relation between the fabric and the rubber of the tube, the fabric being uniformly distributed in the necessary portion of the rim side of the tube in order to protect the same from pinches by the bead of the shoe or from injury through carelessness in placing the tube in position. I have also shown the same to be provided with a plurality of formations suitable for providing an aperture for the reception of the valve base, while the fabric is so arranged as to distribute the elasticity uniformly throughout the length of the tube after the same has been joined together.

60 I claim:

1. A tube for pneumatic tires having its rim side portion protected by diagonally disposed overlapping unconnected means permitting transverse, longitudinal and diagonal expansion thereof.

2. A tube for pneumatic tires having its rim side portion protected by series of longitudinally unconnected diagonal fabric strips imbedded therein adjacent to the surface of the tube.

3. A tube for pneumatic tires having its rim side portion protected by a plurality of series of diagonal superimposed unconnected fabric strips imbedded therein adjacent to the surface of the tube.

4. A tube for pneumatic tires having its rim side portion protected by a plurality of series of diagonal unconnected fabric strips imbedded therein adjacent to the surface of the tube, said series being separated radially by rubber.

5. A tube for pneumatic tires having its rim side portion protected by series of unconnected diagonally overlapping fabric strips imbedded therein adjacent to the surface of the tube the overlapping portions being separated by interposed rubber.

6. A tube for pneumatic tires having its rim side portion protected by series of diagonally arranged discontinuous flexible means embedded therein to permit differential, longitudinal, transverse and diagonal expansion thereof, independently of the remaining portion of the body of the tube.

7. A tube for pneumatic tires having its rim side protected by superimposed separated series of unconnected fabric strips diagonally arranged and imbedded therein adjacent to the surface of the tube to permit limited expansion in all directions independently of the remaining portion of the body of the tube.

8. A tube for pneumatic tires having its rim side portion protected by fabric strips having their lengths disposed diagonally of the tube, the remaining portion of the tube consisting of unrestrained rubber.

9. A tube for pneumatic tires having its rim side portion protected by superimposed series of elongated unconnected fabric strips disposed with their lengths diagonal of the tube and imbedded therein adjacent to the rim side surface of the tube and spaced apart by intermediate rubber.

10. A tube for pneumatic tires having its rim side portion protected by a series of unconnected elongated fabric strips embedded therein adjacent to the rim portion of, and in diagonal lengthwise relation to, the tube, said strips being spaced apart throughout their adjacent edges by intermediate unrestrained rubber.

11. A tube for pneumatic tires having its rim side portion protected by series of diagonally arranged unconnected fabric elements the elements in the different series being oppositely disposed and imbedded therein adjacent to the rim side surface.

12. A tube for pneumatic tires having its rim side portion protected by series of diagonal unconnected fabric elements oppositely disposed respectively in a different series and imbedded therein adjacent to the rim side surface to permit limited expansion, independently, of the remaining portion of the body of the tube.

13. A tube for pneumatic tires having its rim side portion protected by superimposed spaced series of unconnected diagonally arranged overlapping fabric strips

imbedded therein adjacent to the surface of the tube in combination with a valve base overlappingly and yieldingly related with the said protecting strips.

5 14. In combination with a tube for pneumatic tires having its rim side portion protected by overlapping diagonally arranged unconnected series of fabric strips imbedded therein adjacent to the surface 10 of the tube and spaced apart by intermediate rubber, a valve base adapted to receive from without the button of the valve stem, said valve base being overlappingly connected with the said protecting series.

15 15. A tube for pneumatic tires protected by superimposed coextensive series of unconnected diagonal oppositely disposed strips imbedded therein adjacent to the surface of the tube.

20 16. A tube for pneumatic tires having its rim side portion protected by superposed series of diagonally arranged unconnected oppositely disposed fabric strips, said fabric being arranged to provide a plurality 25 of spaces adapted to be apertured to receive the button of a valve stem.

17. In a tube for pneumatic tires a rim side protection consisting of inner and outer series of diagonally disposed fabric strips 30 embedded therein in overlapping relation and separated by intermediate rubber.

35 18. In a tube for pneumatic tires having its rim-side portion provided with embedded, diagonally extended relatively movable flexible means for minimizing expansion on diagonal lines, while permitting longitudinal and transverse expansion.

40 19. A tube for pneumatic tires having its rim-side portion provided with embedded, diagonally extended, relatively movable flexible means disposed in radially overlapping relation, for minimizing expansion on diagonal lines while permitting longitudinal and transverse expansion.

45 20. A tube for pneumatic tires having its rim-side portion provided with embedded, diagonally extended, relatively movable flexible strips disposed in radially spaced series.

50 21. A tube for pneumatic tires having its rim-side portion provided with embedded, diagonally extended, relatively movable flexible strips disposed in radially spaced 55 series, the strips of one series being ar-

ranged in overlapping relation with those of the other series.

22. A tube for pneumatic tires having its rim-side portion provided with embedded, diagonally extended, relatively movable flexible strips disposed in radially rubber-separated series.

23. A tube for pneumatic tires having its rim-side portion provided with embedded, diagonally extended, relatively movable flexible strips disposed in radially rubber-separated series, adjacent edges of adjoining strips being rubber separated.

24. A tube for pneumatic tires having its rim-side portion provided with embedded, diagonally extended, relatively movable flexible strips disposed in radially spaced series, the strips in each series being spaced at their adjacent edges.

25. A rim side protection consisting of 75 series of over-lapping diagonally disposed fabric elements, the elements of each series being separated by strips of rubber, said strips being in angular intersectional relation to similar strips in the other series, providing at the point of intersection yieldingly separable edges adjacent to a valve stem opening.

26. A rim side protection consisting of 85 series of over-lapping diagonally disposed fabric elements, the elements of each series being separated by strips of rubber, said strips being in angular intersectional relation to similar strips in the other series, providing at the point of intersection yieldingly separable edges adjacent to a valve 90 stem opening, a valve base fabric having a slotted portion with a central aperture in radial alignment with said point of intersection.

27. In a tube for pneumatic tires a rim side protection consisting of inner and outer series of diagonally disposed fabric strips embedded therein in over-lapping relation and separated by intermediate rubber and 100 having over-lapping fabric elements for compressing the rubber in the tread side of the tube.

In testimony whereof I have hereunto affixed my signature in the presence of two 105 witnesses.

ALBERT ENNIS HENDERSON.
